UNITED STATES PATENT OFFICE

JAMES A. SHAFER, OF EAST CLEVELAND, OHIO, ASSIGNOR TO NATIONAL MALLEABLE &
STEEL CASTINGS COMPANY, OF CLEVELAND, OHIO, A CORPORATION OF OHIO

LOCK

Application filed May 14, 1929. Serial No. 362,907.

This invention relates to locks and more particularly to a lock which has been developed for holding closed the discharge doors of railway hopper cars. Such locks must perform their functions with unfailing reliability under varying conditions of service and should at the same time be capable of economical manufacture. A lock of this character is disclosed in my copending application Serial No. 280,668, filed May 26, 1928. While the lock shown in said application effectively carries out its intended functions, my present invention provides certain improvements whereby locks of this nature may be simplified in construction and their operation further facilitated. One of the features of the invention is the provision of a locking mechanism which may be assembled at the factory and shipped as a unit for application to the car. My invention also provides improved mechanism for locking and unlocking the door restraining latch, which mechanism is operable with marked facility even by unskilled operators. I further provide a locking mechanism effective in action and at the same time compact in organization and reduced in weight. Other features of the invention will be hereinafter described and claimed.

In the accompanying drawings:

Fig. 1 is a diagrammatic side elevation of a hopper car having locking mechanism embodying the invention applied thereto.

Fig. 2 is a central transverse section of the car shown in Fig. 1.

Fig. 3 is a detail side elevation partly in section of said locking mechanism.

Fig. 4 is a fragmentary transverse sectional view on line IV—IV of Fig. 3.

Fig. 5 is a transverse sectional view on line V—V of Fig. 3.

Fig. 6 is a transverse sectional view similar to Fig. 5 but showing parts of the locking mechanism in a different position.

Figs. 7 and 7^a are detail views on an enlarged scale of the latch pawl.

Fig. 8 is an enlarged scale detail rear view of the latch pawl controlling element.

Fig. 9 is a view in side elevation and on an enlarged scale showing the mechanism in

locked position with the latch pawl advanced one tooth.

Fig. 10 is a transverse sectional view showing a modified form of locking mechanism.

Fig. 11 is a view in side elevation of the 55 modification shown in Fig. 10.

Fig. 12 is a view similar to Fig. 11 but showing the parts in a different position, and

Fig. 13 is a vertical sectional view on line 60 XIII—XIII of Fig. 10.

Referring to Fig. 1 there is illustrated a hopper car, the hoppers 5 of which are closed by discharge doors 6 extending transversely of the car. The doors are arranged in pairs, the two doors of each pair being connected by a door spreader 7 at their lower edges, which spreader is engaged by locks 8 at either end thereof for holding the doors tightly closed.

The lock shown for illustrating the principles of the invention comprises a two-part 70 housing with a latch 10 slidably mounted therein. The latch is engageable with a suitable flange 11 of the door spreader 7, said flange serving as a keeper. The flange may conveniently be formed to lie at an acute 75 angle to the plane of the door, as shown in Fig. 3, but this is not essential. A plate 9 may, if desired, be secured to the hopper wall 5, said plate having a flanged or skirt portion 9' extending beyond said wall and covering 80 the adjacent edge portion of the door 6 when the latter is in closed position, as indicated in Fig. 3; thus aiding in preventing the entrance of dirt and moisture between the door and the hopper and also shielding said door.

The inner housing member 12 is provided with three bosses 13 adapted to space the housing from the side walls of the hopper body; and the outer housing member 14 may have bosses 15 in alignment with said bosses 85 13 and adapted to fit into corresponding recesses 16 in the housing member 12, as indicated in Figs. 5 and 6. Rivets 17 are adapted to be passed through the outer housing member 14 and bosses 13 to secure the housing to the hopper wall as shown. In addition, I provide the outer housing member 14 with a boss 18 extending into a recess 19 in the inner housing member 12; a rivet 20 being passed through said boss and through the member 12, 90 95 100

as shown in Fig. 4, and thereby securing the housing members together. In this way, after the locking mechanism has been assembled in the housing members, the latter may be fastened together by said rivet 20, and the parts shipped in assembled relation for application as a unit to the car; such application being readily effected through the rivets 17. Shipping of the parts in knockdown form, 10 with the consequent necessity of assembly at the car, may thus be avoided.

The latch 10 comprises a longitudinal web portion 21 having oppositely projecting bosses or trunnions 22, 23, which are received in guideways 24, 25 in the inner and outer housing members respectively. The trunnions are preferably elongated as shown to afford extended contact with the guideways. Referring to Fig. 3, it will be seen that the 15 left side of the upper trunnions 22 and the right side of the lower trunnions 23 are parallel to the direction of movement of the latch in the guideways of the housing. These faces of the trunnions are the ones which bear 20 against the guideways and resist the stresses of use tending to open the doors when the parts are in locked relation. The guideway 24, 25 is preferably curved at its upper end in order to increase the gather and permit 25 preliminary catching of the latch with the door farther from its tightly closed position than would be possible with straight guideways.

It will be noted that the operative face of 30 the latch where it engages the door spreader as indicated at 26, lies at an acute angle to the direction of movement of the latch in the guides 24, 25. By this arrangement, when the door approaches closed position, but is 35 still open a substantial distance, the flange 11 of the door spreader can be engaged by the face of the latch 10 and can, therefore, be securely held in this position, or, it can be forced to tightly closed position by forcing 40 the latch downwardly, thus using the lock as a wedging means for completely closing the door. The latch and keeper are formed to provide an extended bearing to insure an 45 effective engagement when the door is locked. The lower end of the latch 10 may conveniently be formed on a curve such that as the door is closed the latch will be lifted automatically by engagement with the flange 11 with the curved lower edge. It is desirable 50 to provide suitable means whereby the latch 10 may be forcibly retracted from locking position to release the door and forcibly moved to locking position, whereby the door 55 may be forced to fully closed position using the lock parts in the operation. As shown, the latch is formed with a suitable apertured extension 27 and the inner housing member 12 is provided with a number of ledges 28 whereby a pinch bar such as is ordinarily 60 carried by operators may be introduced 65

through the extension and into engagement with the ledges to force the latch to or from closed position. The features which have been hereinbefore described in conjunction with the latch 10 are disclosed in my co-pending application previously referred to and are not claimed herein. 70

For locking the latch 10 in door-locking position I provide on said latch a pawl 29 having teeth 30 and movable to bring said teeth into and out of engagement with a series of projections or teeth 31 on the outer housing member 14. The locking pawl 29 is shown pivotally mounted on a boss 32 projecting from the latch 10; said boss passing 80 through an opening 33 in said pawl. The latter, in addition to being turnable about the axis of the boss 32 is also swingable about an axis at right angles to the axis of the boss; movement of the pawl about this latter axis being adapted to effect the engagement and disengagement of the teeth 30 with respect to the teeth 31. Thus, in Fig. 5 the pawl 29 is in engagement with teeth 31, thereby locking the latch 10 against movement; 90 while in Fig. 6 the pawl has been swung about a vertical axis at right angles to the axis of the boss, the teeth of said pawl being now disengaged from teeth 31, and the latch 10 being thus unlocked. To permit such swinging of the pawl 29 the latter is formed with rear faces 34, 35, extending at an angle to each other, and the walls of opening 33 are provided with inclined portions, as indicated at 36, 37, so that when the pawl is in the position shown in Fig. 5, with its rear face 34 contacting the shouldered portion 38 of latch 10 at the base of the boss 32, the wall portions 36, 37 extend at an angle to said boss. The wall of said opening 33 may also be provided with portions 39, 40 extending at an angle to said inclined wall portions, the portions 39, 40 extending parallel to the boss 32 and engaging the same, as shown in Fig. 5, when the pawl 29 is engaged with the teeth 105 31. When the pawl 29 is turned into the position shown in Fig. 6, wherein its teeth have been disengaged from teeth 31, the rear face 35 of said pawl contacts with the aforesaid shouldered portion 38 of latch 10. 110

The operation of the locking pawl 29 is controlled by a manually operable member 41 pivotally mounted on the boss 32 and positioned adjacent said pawl. The member 41 and pawl 29 are held in assembled relation on boss 32 by washer 42 and rivet 43, the latter passing through said washer and through the boss 32 as shown in Figs. 5 and 6. Said pawl-controlling member 41 includes a counterweighted portion 44 to facilitate its operation, said portion also having an inclined surface 44' for a purpose which will later appear. Also, said pawl controlling member is provided on its rear face with an inclined surface 45 terminating in a lug 46. 125

The front face of the pawl 29 is likewise provided with an inclined surface 47.

Assuming the parts to be in the position shown in Fig. 6, the latch retracted, and the hopper door open, upon closing the door the latch may be moved downwardly and engaged with the flange 11 of spreader 7, as shown in Fig. 3, wedging the door tightly against the hopper. The counterweighted portion 44 of the pawl controlling member 41 is now grasped and said member is swung to the left into the position shown in Fig. 5. During this movement the lug 46 acts upon the surface 48 of the pawl 29 to rock the latter inwardly into engagement with the teeth 31, and the forcing of said pawl into such engagement is further assisted by inclined surface 44' of counterweight 44 which comes into engagement with and acts upon surfaces 49' and 49 of said pawl. When the member 41 reaches the position shown in Figs. 3 and 5 the pawl 29 is firmly and fully meshed with teeth 31 and the latch 10 is effectively locked against retraction. It may be noted that the edge 50 of the member 41 now engages a ledge 51 projecting from the latch 10. As long as said member remains in the position shown in Fig. 5 it locks the pawl 29 against disengagement from the teeth 31.

If the latch 10 should be in such position that the teeth 30 of pawl 29 are not properly aligned with the spaces between the teeth 31, so that the pawl cannot be meshed with said teeth, the operator can lift said pawl with his fingers, turning it about the axis of the boss 32, and bringing it into proper relation to said teeth 31; and said pawl can then be engaged with said teeth by operation of member 41 as aforesaid. Thus, if the pawl 29 is not in proper relation to teeth 31 for being meshed with the same, it is unnecessary to shift the latch from its operated position to bring said pawl into said relationship, but such may instead be effected by simply turning the pawl the appropriate amount about the boss 32. This adjustment of the pawl may be effected with convenience and facility, said pawl being readily accessible for manipulation by the operator and the teeth of said pawl as well as the cooperating teeth 31 being plainly visible. In Fig. 9 the mechanism is shown in locking position with the pawl advanced one tooth beyond its normal (Fig. 3) position. To prevent adjustment of the pawl about the boss 32 to such an extent that it becomes inoperative, said pawl is provided with an extension 52 which limits the clockwise movement of the pawl by coming into contact with the ledge 51 of the latch.

To unlock the latch, the pawl-controlling member 41 is thrown to the right from its Fig. 5 position to its position shown in Fig. 6. During this movement the lug 46 engages the inclined surface 47 of said pawl and forces the teeth 30 out of engagement with

teeth 31. The latch 10 is now free to be retracted to unlock the hopper door.

To facilitate opening of the door in case it should stick after the latch 10 has been raised, as for example if the door should be frozen shut, I have provided on the lower portion of housing member 14 a lug 53. This lug provides a fulcrum for a pinch-bar, the end of which may bear against the surface 54 of the spreader flange 11, whereby the door may be readily pried open.

In Figs. 10-13 I have shown a modified form of my invention wherein the locking pawl may be slid instead of tilted into and out of engagement with the teeth 31. As shown in the views referred to, the pawl 29' is provided with an elongated opening 33' through which passes the boss or trunnion 32 on the latch 10. Also, said pawl is formed with shoulders 55, 56 adapted to be engaged by a laterally projecting arcuate extension 57 on the latch pawl controlling member 41'. The arcuate surface of the extension 57 aforesaid is eccentric with respect to the longitudinal central axis of the boss 32, as the result of which it will be seen that turning of the control member 41' about said boss will result in sliding movement of the pawl 29'. With the parts shown in Figs. 10 and 11, in order to disengage the pawl 29' from the teeth 31, the member 41' is thrown to the right through 180°; during which movement the extension 57 will come into engagement with the pawl shoulder 56 and shift said pawl to the right, thereby disengaging its teeth from the teeth 31 on the housing member 14. The parts are now in the position shown in Fig. 12. To lock the mechanism the member 41' is thrown 180° to the left from its Fig. 12 position to that shown in Fig. 11; the extension 57 acting upon the shoulder 55 to force the pawl into engagement with teeth 31 aforesaid. Should the latch be in such position that the pawl teeth 30 are not in proper meshing relation with teeth 31, the pawl may be readily turned about the boss 32 to bring its teeth into alignment with the spaces between teeth 31 in the same manner as has been previously pointed out in connection with the pawl 29.

The terms and expressions which I have employed are used as terms of description and not of limitation, and I have no intention, in the use of such terms and expressions, of excluding any mechanical equivalents of the features shown and described or portions thereof, but recognize that various structural modifications are possible within the scope of the invention claimed.

What I claim is:

1. In a lock for the discharge door of a hopper car, a latch for locking said door, means comprising interengageable elements for locking said latch, and means whereby if said elements are out of proper relation for 13.

locking engagement in a given position of said latch said relation may be established without shifting the latch from said position.

- 5 2. In a lock for the discharge door of a hopper car, a latch for locking said door, means for locking said latch, said means comprising a movable element and a member engageable thereby, and means whereby said element may be adjusted to proper position for engagement with said member independently of said latch.
- 10 3. In a lock for the discharge door of a hopper car, a latch for locking said door, a movable member for locking said latch, a retaining element for retaining said movable member in locking position, and means whereby shifting of said retaining element causes movement of said locking member.
- 15 4. In a lock for the discharge door of a hopper car, a latch for locking said door, a toothed element movable with said latch, a second toothed element engageable by the first mentioned element for locking said latch, and means whereby relative adjustment of said elements to bring the teeth thereof into proper relation for interengagement may be effected for a given position of said latch without shifting the latch from said position.
- 20 5. In a lock for the discharge door of a hopper car, a latch for locking said door, an element movable with said latch, a second element engageable by the first mentioned element upon movement thereof in a given direction for locking said latch, and means whereby said first mentioned element may be shifted in a different direction for establishing proper interengaging relationship between said elements.
- 25 6. In a lock for the discharge door of a hopper car, a latch for locking said door, an element movable with said latch, an element engageable by the first mentioned element for locking said latch, said first mentioned element being shiftable in one direction to establish proper engaging relationship with the second mentioned element and being shiftable in a different direction to engage said element.
- 30 7. In a lock for the discharge door of a hopper car, a latch for locking said door, a toothed pawl pivotally carried by said latch, a toothed element engageable by said pawl, and means whereby when said pawl and element are out of engaging relation in a given position of the latch, such relation may be established without shifting the latch from said position.
- 35 8. In a lock for the discharge door of a hopper car, a latch for locking said door, a toothed pawl pivotally carried by said latch, an element engageable by said pawl for locking said latch, said pawl being shiftable about its pivot in one direction for establishing an engageable relation with said element, and

being shiftable about its pivot in another direction for engaging said element.

9. In a lock for the discharge door of a hopper car, a latch for locking said door, a pawl carried by said latch for locking the same, and a shiftable element carried by said latch for controlling said pawl. 70

10. In a lock for the discharge door of a hopper car, a latch for locking said door, a pawl carried by said latch for locking the same, and a shiftable element carried by said latch for operating said pawl and for retaining the latter in operated position. 75

11. In a lock for the discharge door of a hopper car, a latch for locking said door, means for locking said latch, said means comprising a pawl, and a toothed element engageable thereby, and a member adapted to hold said pawl in engagement with said element, said member being provided with camming means for effecting disengagement of said pawl from said element. 80

12. In a lock for the discharge door of a hopper car, a latch for locking said door, a pawl pivotally carried by said latch and adapted to lock the same, and a pawl controlling member mounted on said latch coaxially with said pawl. 85

13. In a lock for the discharge door of a hopper car, a latch for locking said door, a pawl pivotally carried by said latch, an element engageable by said pawl for locking said latch, said pawl being turnable about its pivot into proper engaging relation with said element, and means co-axial with said pawl for shifting the latter into engagement with said element after said engaging relation has been established. 95

14. In a lock for the discharge door of a hopper car, a latch for locking the door, a pawl carried by said latch, an element engageable by said pawl for locking said latch, said pawl being shiftable on said latch into proper engaging relation with said element, and a member cooperating with said pawl for shifting the latter into engagement with said element after said relation has been established. 105

15. In a lock for the discharge door of a hopper car, a latch for locking the door, a pawl carried by said latch, an element engageable by said pawl for locking said latch, said pawl being shiftable on said latch into proper engaging relation with said element, and a member mounted on said latch and cooperating with said pawl for shifting the latter into engagement with said element after said relation has been established. 110

16. Means for facilitating the opening of a discharge door on a hopper car, said means comprising an extension on the spreader associated with said door, and a projection on the hopper adjacent to said extension and providing a fulcrum for a bar for cooperation with said extension to force the door out of 125

closed position, said projection being so disposed with respect to said extension that a horizontal plane passing through said extension also passes through said projection.

5 In testimony whereof, I have signed my name to this specification this 7th day of May, 1929.

JAMES A. SHAFFER.
